UNITED STATES PATENT OFFICE.

CHRISTOPHER C. BRADLEY, OF SYRACUSE, NEW YORK.

DESIGN FOR A DRAFT-EYE FOR VEHICLE-SHACKLES.

SPECIFICATION forming part of Design No. 33,379, dated October 16, 1900.

Application filed September 24, 1900. Serial No. 31,006. Term of patent 14 years.

To all whom it may concern:

Be it known that I, CHRISTOPHER C. BRADLEY, a citizen of the United States, residing in Syracuse, in the county of Onondaga and State of New York, have invented and produced a new and original Design for Draft-Eyes for Vehicle-Shackles, of which the following is a specification, reference being had to the accompanying drawings, forming a part thereof.

Figure 1 is a top plan view, and Fig. 2 is an end view thereof looking at Fig. 1 from the right.

As shown in the accompanying drawings, the leading or material feature of my design consists of an angular or L-shaped draft-eye and comprises the bar *a*, having an eye *b* ex-

tending at substantially a right angle from one end thereof, one side of the eye having a spherical knuckle *c*, all formed and stamped up from a single piece of metal, the whole forming a unique unitary article of manufacture.

Having thus described my invention, what I claim, and desire to secure by Letters Patent, is—

The design for a draft-eye for shifting vehicle-shackles as herein described and shown.

In witness whereof I have hereunto set my hand this 18th day of September, 1900.

CHRISTOPHER C. BRADLEY.

Witnesses:

MILDRED M. NOTT,
HOWARD P. DENISON.
